(57) **CLAIM**

The ornamental design for a contact isolator, as shown and described.

DESCRIPTION

FIG. 1 is a top front perspective view of a first embodiment of a contact isolator in an open configuration showing the new design;

FIG. 2 is a bottom front perspective view thereof;

FIG. 3 is a top back perspective view thereof;

FIG. 4 is a front plan view thereof;

FIG. 5 is a back plan view thereof;

FIG. 6 is a left side end view thereof;

FIG. 7 is a right side end view thereof;

FIG. 8 is a bottom view thereof; and,

FIG. 9 is a top plan view thereof.

The broken line portion of the figure drawings is included to show unclaimed subject matter only and forms no part of the claimed design.
